UNITED STATES PATENT OFFICE

WILLIAM ERASTUS WILLIAMS, OF WILMETTE, ILLINOIS, ASSIGNOR TO DITTO, INCORPORATED, OF CHICAGO, ILLINOIS, A CORPORATION OF WEST VIRGINIA

HECTOGRAPH DUPLICATING COPYING MACHINE

Application filed February 4, 1928. Serial No. 251,927.

My invention relates to machines which use a gelatin pad sheet of the hectograph type which is in the form of a band adapted to be rolled from one spindle to another over an impression bed and the machine is provided with an impression carriage carrying a platen impression roll and adapted to impress paper onto the gelatin pad sheet on the bed and make copies by this method.

10 The object of my invention in general terms is to improve the detailed mechanisms of such a machine in a manner to lessen the cost and increase the efficiency and convenience of operating.

15 One of the principal objects is to control the platen roll to prevent its revolving to displace the register of the sheet to be copied as relates to the master copy which is first laid down on any given portion of the gelatin pad on the bed.

20 Another object of prime importance is to mount the carriage upon the machine in a manner that it may be freely and easily operated and be convenient for mounting and 25 dismounting from the bed frame, as desired in transit or for cleaning and for repairing the parts.

Another object of the invention is to provide means for raising and lowering the carriage for clearance purposes in training the gelatin pad sheet over the bed and other objects will be described in detail in the body of the specification and set forth in the claims.

Reference will be had to the accompanying 35 drawings in which Fig. 1 is a plan of the machine, in which the right side of this figure is called the front of the machine, and the left side the rear and the position of the carriage on the bed in this figure is that shown in 40 Fig. 5.

Fig. 2 is a side elevation of the machine looking from the left side of the machine.

Fig. 3 is a plan detail of a part of the mechanism which controls the platen roller as the 45 same is moved upward and downward in impressing the paper to the gelatin pad sheet on the bed.

Fig. 4 is a sectional elevation through the impression carriage on line 4—4 of Fig. 1 50 showing the platen roll in a raised position

whereat the paper is inserted ready for commencement of an operation of making a copy.

Fig. 5 is a similar view to that of Fig. 4 but shows the position of the parts after the paper has partly been impressed by the platen roll 55 onto the gelatin pad sheet, in other words, in the act of impressing the paper to the gelatin pad sheet.

Fig. 6 is a sectional elevation on line 6—6 of Fig. 1.

Fig. 7 is a transverse section on line 7—7 of Fig. 6.

Fig. 8 is a vertical elevation at the right side of the machine on line 8—8 of Fig. 1.

The machine is provided with the side 65 frame members, the left one being indicated by 1 and the right one by 2, and these frame members are supported on legs 3 and are connected across by cross tie bars 4 and a front end tie bar 5. At the top end corners of 70 the frame members 1 and 2 there are secured blocks 6 (see Figs. 6 and 7) to which are fastened bars 7 one on each side upon which there is fastened the iron bed plate 8 by screws 9 which bed plate forms the impression bed of the machine. Over the top of this bed plate there is stretched a felt cloth 10 75 which has its edges turned under as indicated by 11 and secured to the bed plate, the purpose of the cloth being to furnish a cushion or elastic sheet for the impression service. Over the bed there is stretched a web or gelatin pad sheet 12 extending from a spindle 13 at the rear of the machine up over the roller 14 onto the bed herein generally 80 mentioned as 8 and thence over a crossbar 15 at the front end of the bed which crossbar 15 takes the place of the roller 14, as it were, of the bed and thence down to the spindle or reel 16 at the front of the machine. Thus 85

the gelatin pad sheet is trained as used from spindle 13 to the spindle 16. These spindles are provided with little gudgeons 17 which at the right side of the machine or the location of the frame member 2 are supported 90 in small holes in blocks 18 secured to spring arms 19 secured to blocks 20 to the frame member 2. The blocks 18 are provided with inclined guiding recesses 21 that assist in directing the gudgeons 17 into perforations 100

in blocks 18 in the act of entering the spindles into position. The left end of the spindles are supported in short shafts 22 (see Fig. 7) at each end of the machine on the left side 5 and these short shafts 22 are mounted in a keeper plate 23 in the side frame of the machine and are provided in the inside with ratchets 24 and 25 respectively, the ratchet 24 being controlled by a pawl 26 and it in 10 turn by a bar 27 (see Fig. 2) connected to an operating handle 28 which permits the disengagement of the pawl 26 from the ratchet 24 as desired. The ratchet 25 is controlled by a pawl 29 and on the outside of the 15 frame member 1 there is provided operating hand wheels 30 and 31 by means of which the gelatin pad sheet may be moved over the bed 8 as desired, and held in place in any given position. Upon the bars 7 there are 20 mounted rack strips or bars 32 (see Figs. 1 and 7) which are provided with perforations 33 on their edges which function as ordinary gear rack teeth. The location of the bars 32 leave apertures 34 at each side of the machine as best observed by Fig. 1. The impression carriage is composed of the end plates 35 and 36 connected together across by a cross frame member 37 which acts as a paper guide for the paper sheets 38 that are used in 25 the machine (see Figs. 4 and 5). This cross frame member 37 has end flanges 39 by means of which it is secured in any suitable manner to the end plates 35 and 36 and it also has a cross stiffening flange 40 in which there is a 30 slot 41 for the purpose of holding a clamping bolt 42 which clamps the flange 43 of a side paper guide strip plate 44 which has a guide flange 45. The bolt 42 is provided with a cam lever 46 by means of which the side 35 paper guide 44 with its flange 45 may readily be adjusted for a side adjustment of the paper sheet 38 as the same is inserted in the machine. The impression carriage is supported at its rear end on a shaft 47 extending through 40 the end plates 35 and 36 and the flanges 39 of the cross frame member 37 and the shaft 47 has mounted on each end and fixed thereto to revolve with the shaft, pin gear wheels 48 having pin teeth 49 adapted to engage 45 rack holes 33 in the same manner as an ordinary gear and rack might do, the difference being that the wheels 38 have their tread portions 50 on what is substantially the pitch line were the gears made of the standard gear teeth. The tread portions 50 riding on top of the rack bars 32 substantially in the same manner as an ordinary wheel might ride while the pin gear teeth 49 are shaped substantially in the outline of what might be 55 or is a normal addendum of a gear tooth. Thus, as the impression carriage is moved backward and forward over the bed, the wheels 48 with their teeth 49 and tread surfaces 50 cause each side of the carriage to 60 move backward and forward squarely and

easily owing to the fact that the said gear wheels 48 are fixed to the cross shaft 47. On the ends of the shaft 47 there is mounted end plates 51 through the medium of hub blocks 52 secured to the end plates by rivets or other suitable means. However, these hub blocks may be cast integral if castings are used for these end plates. End plates 51 are provided with flanges 53 which cover up and act as shields for the pin gear wheels 48. The 70 end plates 51 are held onto the shaft by collars 54 and the shaft 47 revolves in the hubs 52 thus permitting the end plates 51 to ride always in the same position in relation to the side frame members. In front of the gear 75 wheels 48 there are mounted small pin wheel gears 55 similar in construction to the gears 48 and are mounted as idle gears on the little studs 56 fixed into the end plates 51. The lower edges 57 of the end plates 51 extend 80 down into the apertures 34 and the flanges 53 are wanting for this distance and fixed into these lower ends 57 there are small studs 58 on which are mounted little idle wheels 59 (see Fig. 8) which hold the end plates 35 85 and 36 of the carriage onto the rack bars 32. At their front ends the end plates 35 and 36 of the carriage have short turned over flanges 60 and 61 which when the carriage is home at the front of the machine abut against rubber 90 abutment blocks 62 and 63 which blocks are secured to peculiarly shaped angle blocks 64 and 65 and these blocks 64 and 65 have projections 66 which extend down through apertures 34 and underneath the bars 32 (see Figs. 95 7 and 8) which hold the abutment blocks in position to be slid backward and forward longitudinally on the rack bars 32. Cam hand levers 67 having small cam blocks hinged at 100 68 clamp the abutment blocks in any given position backward or forward along the bars 32.

A similar abutment or stock block 69 is supported on the block 70 which is secured by a thumb screw 71 in any desired position 110 along the rack bars 32 for a backward or rear stop for limiting the outermovement of the carriage on the bars 32 (see Fig. 2).

The paper 38 (see Fig. 4) which is to be 115 acted upon by the machine is positioned by the operator against a standard margin bar 72 which bar is supported by links 73 hinged at 74 into the bars 7 and the paper is impressed upon the gelatin pad 12 by means of a rubber faced impression roll 75 which is 120 supported in the bearings in arms 76 and 77 of a yoke composed of the said arms 76 and 77 mounted on a hollow shaft 78 (see Fig. 1) which shaft is supported in journal boxes 79 in the end plates 35 and 36 of the carriage. 125 This shaft is vibrated by means of a hand lever 80 having a hand shield 81 and fixed to the shaft 78 in any suitable manner by a block 82 shown in dotted lines in Fig. 5. By 130 this means the platen roll 75 is vibrated across

from the position of Fig. 4 to that of Fig. 5 while the body of the carriage itself remains in the position of Fig. 4 and then upon the completion of the movement of the platen roll from Fig. 4 down onto the gelatin pad 12 the operator moves the carriage forward or outward and impresses the paper upon the gelatin pad 12.

In moving the platen roll 75 from the position of Fig. 4 to that of Fig. 5 the paper is clamped by a clamping roll 83 which is supported by journals in bearing blocks 84 hinged at 85 to the plates 35 and 36 of the carriage and the blocks 84 are provided with lever ends 86 through which bolts 87 pass down and thru the cross frame member 37 and have upon their ends threaded springs 88 adjusted by the nuts 89 to properly produce the spring tension desired for clamping the roll 83 to the platen roll 75. Set screws 90 limit the movement of the clamping roll 83 and prevent any excess movement of the roll 83 out of place when the platen roll is in the position of Fig. 4.

As the platen roll 75 descends from the position of Fig. 4 as the operating handle is moved for that purpose, and as the platen roll 75 pushes the paper in contact with the clamping roll 83, the normal tendency is for the roll 75 to revolve backward or clockwise from the position shown in Fig. 4 and in this movement will displace or withdraw the registration of the paper from the margin bar 72.

To prevent such a movement or any movement of a revolving character of the platen roll 75 in its descent from the position of Fig. 4 of clamping the paper there is provided a brake clamping mechanism or dental clutch (as shown in Fig. 3) one member 91 of this

40 brake or dental clutch being secured to the platen roll 75 and the other member 92 being mounted on the axis 93 of the platen roll to move longitudinally of the said axis but is prevented from revolving by pins 94 which

45 are secured in apertures in the block 92 and into a lever 95 hinged at 96 to the arm 77 of the main yoke which carries the platen roll 75. Thus the lever 95 prevents the revolution of the block 92 and at the same time

50 presses the block 92 when permitted to do so into engagement with the block 91 through the medium of a spring 97 on a pin 98 which is fixed in the block 77 and passes through a

55 perforation in the lever 95. The other end of the lever 95 at 99 is secured to a projection 100 which is engaged by a shoulder 101 of a peculiarly shaped lever block 102 hinged at 103 to the plate 36 of the carriage (see Figs. 4 and 5).

60 The lever 102 is provided with a lip 104 which is engaged and pressed downward by a spring 105 secured at 106 held downward by a screw 107 whenever permitted to do so until this movement is arrested by a pin 108 in end plate 36. The lever 102 is

65 provided with a downwardly extending end

109 (see Figs. 4 and 5) which when the carriage is home backward in position to receive the paper, as shown by Fig. 4, abuts against the abutment block 62 and thereby lifts the lever 102 clear of the pin 108 lifting the spring 105 which then allows the coil spring 97 (see fig. 3) to push the lever 95 to move the block 92 to engage with the block 91 and thus holds the platen roll 75 from revolving movement in either direction and this engagement of the two blocks 91 and 92 remains in engagement so long as the carriage is back against the abutment blocks 62 and 63 which is in the location whereat the paper 38 is placed in the machine. Then after the paper is down upon the gelatin and the carriage is moved forward the first very slight movement forward or outward of the carriage clears the end 109 from the abutment block 62 which then permits the spring 105 to overcome the spring 97 and disengage from each other the brake or dental clutch blocks 91 and 92 which then permits the platen roll 75 to revolve freely in laying down the paper and withdrawing the same on the return stroke of the carriage. Thus the platen roll at all times is permitted to revolve freely without resistance from the brake or dental clutch blocks 91 and 92 save only when the carriage is home against the abutment blocks 62 and 63 at which position the spring 105 is moved to permit the coil spring 97 to force the blocks 91 and 92 together.

When the carriage is back in the position of Fig. 4 and the operator commences to move the handle 80 to move the platen roll 75 down to contact with the paper in order to prevent the carriage moving bodily forward in such a movement of the hand lever 80, I provide a delaying spring 110 secured by screws 111 to the block 64 and this spring has a projection 112 which engages the turned over flange 61 of the carriage end plate 36 (see Fig. 1).

As the carriage is moved outward in laying down the paper as shown in Fig. 5 and then withdrawn to draw the strips of paper from the gelatin pad, the action of the handle 80 in withdrawing home of the carriage tends to lift the platen roll from the gelatin pad 12 and to prevent this lifting movement there is provided at the right end of the hollow shaft 78 and outside the carriage end plate 36 an arm 113 (see Fig. 8) and this arm is engaged by catch blocks 114 two in number, one having a shoulder 115 and the other having a shoulder 116. These catch blocks are hinged on a pin 117 in the plate 36 and are provided with the downwardly extending legs 118 with projections 119 which pass through notches in the flange 61 and are engaged by abutment block 62 (see Figs. 1, 4, 5 and 8) whenever the carriage is home which brings the position of the blocks 114 to that of Fig. 8 but whenever the carriage is moved

115

120

125

130

away from the position of Figs. 4 and 8 the blocks 114 drop down bringing their engaging shoulders 115 and 116 into contact with the end of the lever 113 and thus, as it were, hold the platen roller down onto the gelatin pad at all times when it has been pushed down and moved forward from the registering position of Figs. 4 and 8. Thus insuring that the platen roll will always remain snugly in contact with the gelatin pad portion 12 as the carriage is drawn homeward pulling the paper free of the gelatin pad. The variations between the shoulders 115 and 116 are to insure a close locking of the arm 113 to accommodate wide variations in the thickness of paper used with the machine.

In order to enter the end of the gelatin pad rolls onto and over the impression bed and under and through the impression carriage, it is necessary to rock the carriage in a manner to lift the platen roll 75 and shaft 78 and compression roll 83 high enough to clear the entrance of the gelatin pad roll spindle and to do this the carriage is hinged onto the end plates 51 using the shaft 47 as the said hinge. Then as the carriage is dropped down to working position as shown by Fig. 8, the bracket blocks 120 are fastened to the flanges 53 and resting upon these brackets 120 of the plates 51 are the lower ends of levers 121 which are fixed on a small shaft 122 which passes through the hollow shaft 78 and thus the front end of the carriage is supported when the platen roll is down in working position and the carriage is held downward in this position by means of projections 123 of the levers 121 which engage notches in the said flanges 53 and thus when the position is that of Fig. 8 the plates 51 and 35 and 36 of the carriage are fixed together which hold the carriage frame in working position of laying on and taking off the paper from the gelatin pad sheet. However, when it is desired to enter the end of a new gelatin pad roll the levers 121 are pulled outward against the compression of a small spring 124 (see Fig. 2) releasing the projections 123 and thus permitting the front end of the carriage or the left end shown in Fig. 8 to be raised from the position of Figs. 4, 5 and 8 to that shown by Fig. 6 and when in position of Fig. 6 a catch lever block 125 engages a notch 126 in the flange 53 of the left end plate 51 (see Fig. 1) and thus holds the carriage up to the position of Fig. 6 which permits clearance underneath the carriage for the admission of the spindles upon which the gelatin pad sheets are wound in training a fresh gelatin pad sheet in the machine. A small spring 127 (see Fig. 2) holds the catch block 125 in position when in service of holding the carriage as shown by Fig. 6.

The arrangement of the pin gears and the perforations which act as the rack teeth is especially desirable in a machine of this class as the perforations will clear themselves of

any dirt or foreign matter that may accidentally enter the perforations as the pins of the gears will push this material through the perforations whereas, if ordinary rack teeth are used, there is a constant menace of foreign matter getting into the base of the teeth and causing trouble. The gelatin pad material used in machines of this class under certain temperatures and conditions of weather get very gummy and particles are displaced and gum up the machine many times in a very serious manner and these racks as composed of perforations, the gears having pins for teeth defend against carelessness of all sorts in the use of the machine.

These machines are largely used by boys and girls, many of whom have no idea as to keeping a machine free from foreign obstructions and dirt of all kinds.

Not only that, the pin gears serve a double function since the pins working in pin holes not only hold the carriage squarely as it moves backward and forward over the bed, but they also hold the carriage against lateral displacement across the bed thus making unnecessary any flanges on the supporting wheels or side bearing surfaces for holding the carriage in place as all those extra things create some friction and wear to some extent and cost more money to build than the gears and racks by pins and perforations herein set forth.

Further, the perforations may be punched by gang punches and dies and thus make a cheaper construction than is normally possible to provide a rack for the same purpose when it is provided that the rack shall be self-clearing, as it were, to the extent that a rack of perforations may clear itself.

Further, were the regular rack teeth used in place of the perforations as herein shown, the teeth standing up in any relationship as an equivalent of the arrangement shown herein looks badly and the teeth are liable to catch on the sponge and clothing of the operators since in these machines the gelatin pad is washed and moistened by hand or the moisture, if applied by mechanism, is rubbed in by hand and further in applying the master copy on the machine it is rubbed down by hand causing the operator to move his hands and arms more or less frequently over the bed of the machine and the perforations which act as racks do not in any manner catch on the sponge or clothing of the operator as regular rack teeth might which makes the use of the racks in forms of perforated bars a great desideratum in a machine of this class.

Claims:

1. In a machine of the class described, a platen roll, a brake block moving longitudinally of the axis of the roll and adapted to clamp and prevent rotary movement of the roll as the same is moved bodily up and down impressing the paper onto the gelatin pad

and means for disengaging the said brake block to permit the revolution of the said roll freely as the paper is impressed upon the gelatin pad sheet.

5. In a device of the class described, a platen roll, a brake block adapted to clamp the end of the platen roll and prevent its revolution by means of an endwise clamping movement as relates to the roll, a spring for actuating this clamping movement and another spring for releasing the movement and the latter spring adapted to overpower and control the first mentioned spring.

10. In a device of the class described, a platen roll, a brake block having dental teeth therein and adapted to be moved longitudinally of the axis of the roll in clamping the said clamping roll from revolving movement and means for disengaging the said clamping means of the said brake block.

15. In a device of the class described, a platen roll, mechanism for clamping the said platen roll to prevent rotary movement and said clamping mechanism moving endwise as relates to the length of the platen roll, a spring mechanism for engaging the said clamping mechanism and a spring mechanism for disengaging the said clamping mechanism and a stop block for disengaging 20 the said last mentioned spring mechanism whereby the first mentioned spring mechanism is permitted to act in the clamping function.

25. In a device of the class described, an impression carriage, a platen roll mounted in said carriage, means for raising and lowering the said platen roll in the function of impressing paper on the gelatin pad sheet, a brake mechanism for preventing revolution 30 of the said platen roll in the act of clamping the paper to the gelatin pad sheet, said brake mechanism moving endwise of the roll, a spring mechanism for engaging the said brake mechanism, a lever mounted on the said 35 carriage and actuated by a spring and provided with means for engaging and releasing the said brake mechanism and a block on the frame of the machine adapted to engage the said lever as the carriage is brought to home 40 registering position against the said block.

45. In a machine of the class described, a platen roll adapted to be raised and lowered bodily in impressing the paper to a gelatin pad, a brake mechanism for preventing the 50 revolution of the said platen roll in the movement of impressing the paper upon the said pad, said brake mechanism provided with a brake block mounted to slide longitudinally on the shaft of the said platen roll and said 55 brake block held from revolution by means of a lever hinged to the yoke which carries the platen roll and said lever actuated by a spring to move the said brake block to braking engagement and said lever to move to 60 disengage the said brake block by a secondary

lever hinged to the carriage in which the said yoke is supported and said secondary lever actuated in one direction by a spring and in the other direction by contact with a block on the main frame of the machine.

70. In a machine of the class described, an impression bed on which there is mounted a gelatin pad with trackways on each side of the said bed, the said trackways provided with perforations arranged to act in the place of rack teeth, a carriage mounted over and across the said bed and provided with pin gears one for each trackway and mounted and fixed to a shaft extending across the bed and upon which an impression carriage is mounted, and said pin gears adapted to engage the said perforations which perform the function of racks, said gears being arranged in sets of two at each end of said carriage whereby said carriage is held in proper alignment during its movement along said bed.

75. In a machine of the class described, an impression bed, trackways on each side of said bed upon which an impression carriage is mounted, perforations in the said trackways acting as rack teeth and adapted to be engaged by gears and said gears mounted on and supporting an impression carriage, said gears being arranged in sets of two at each end of said carriage whereby said carriage is held in proper alignment during its movement along said bed.

80. In a machine of the class described, an impression bed, trackways on each side of the said bed provided with perforations adapted to act in place of rack teeth, an impression carriage mounted on a shaft extending across the said bed and having gear wheels fixed to the said shaft and teeth adapted to engage the said perforations in the said trackways, end plates mounted on the ends of the said shaft and also having gear wheels fixed to the said end plates and adapted to engage the perforations in the said trackways and locking means for locking the frame of the carriage in different positions about the said cross shaft as a hinge center as relates to the said end plates.

85. In a machine of the class described, an impression bed, trackways on each side of the said bed provided with perforations adapted to act as rack teeth, an impression carriage mounted over the said bed and mounted on a cross shaft and said cross shaft having wheels with teeth adapted to ride upon the said trackways and the teeth engaging said perforations, end plates mounted on the said shaft and extending down over the edges of the said trackways and provided with anti-friction rollers engaging underneath the said trackways and with secondary idle wheels riding on the tops of the said trackways and supported on studs in the said end plates.

90. In a machine of the class described,

an impression bed, trackways on each side of said bed provided with perforations adapted to act as rack teeth, an impression carriage mounted over said bed and mounted on a cross shaft and said cross shaft having wheels with teeth adapted to ride upon said trackways and the teeth engaging said perforations, and end plates mounted on said shaft and extending down over the edges of said trackways and provided with abutment means disposed underneath said trackways to limit lifting movement of said carriage and with secondary idle wheels riding on the tops of said trackways and supported on studs in said end plates.

Signed at Chicago, in the county of Cook and State of Illinois, this 16th day of January, 1928.
